UNITED STATES PATENT OFFICE.

EMANUEL M. COOK, OF INDIANAPOLIS, INDIANA.

ELEMENT FOR AUTOMATIC FIRE-EXTINGUISHERS.

1,155,339.

Specification of Letters Patent.

Patented Oct. 5, 1915.

Application filed December 28, 1914. Serial No. 879,854.

To all whom it may concern:

Be it known that I, EMANUEL M. COOK, a citizen of the United States, residing in Indianapolis, in the county of Marion, in the State of Indiana, have invented certain new and useful Improvements in Elements for Automatic Fire-Extinguishers, of which the following is a specification.

Sprinkler heads, fire doors and other devices used in automatic systems for protecting buildings against fire usually have an element for holding the door, the cap of the sprinkler head, or some other part in normal position until the element is subjected to a predetermined temperature. These elements are made up of a plurality of parts secured together by solder fusible at a low temperature. The properties of this solder are such that it is subject to "cold flow", which permits the parts to "creep" relatively to each other and the objections to this are well known in the art. It is essential in elements of the class in question that the parts be held in their normal positions with absolute certainty until subjected to the predetermined temperature aforesaid and is equally as essential that when said temperature is reached the parts shall separate, so that the element will release the part which it normally holds in normal position.

The object of all inventions in this class of devices is to accomplish these results and the object of the present invention may therefore be said to be to accomplish them with greater certainty than has been heretofore attained.

To this end the invention consists in the features of novelty that are hereinafter described with reference to the accompanying drawing which is hereby made a part of this specification and in which:

Figure 1 is an axial section on an enlarged scale of a sprinkler head having an element of the link type embodying the invention. Fig. 2 is a perspective view of one of the two similar principal parts or plates of which the element is made up. Fig. 3 is an axial section of a sprinkler head of the strut type, such as is used in sprinkler heads, embodying the invention.

The improved element is made up of two parts, A and A' of identical construction which are in the nature of overlapping plates having the features hereinafter described, and a third part, B, hereinafter called a rocking strut, which is in the form

of a short rod or bar, preferably of elliptical shape in cross section, and of a length just equal to the width of the plates, A, A'.

Each of the plates is offset at right angles, 60 on opposite sides of its mid-length to provide on its inner face a shoulder (C or C') the working face of which is at right angles to the contacting inner faces of the plates, the plates being arranged with the flat inner faces of their end portions squarely in contact with each other and secured together by a thin film of solder fusible at a predetermined low temperature. The shoulders are located at equal distances from the mid-length of the plates and are of a depth equal to the width of the rocking strut, B, thereby forming a recess or pocket which is occupied by said rocking strut which latter is held in place by solder of the kind above 75 mentioned. Each of the plates has near one of its ends an opening (D, D') and has at its opposite end a slot (E, E'). The plates are reversely arranged (i. e. the opening of one is opposite the slot of the other) and 80 the slots which extend to the ends of the plates in which they are respectively formed receives the outer portions, f, of the lever arms, F and F', of the toggle G, of the 85 sprinkler head (in this embodiment of the invention). Said outer portions, f, extend through the openings of the plates and have concave seats for bearing against the plates at the outer ends of the openings through which they pass.

The part, B, has been termed a "rocking strut" because in the normal condition of the parts it performs the function of an absolutely rigid strut which receives the strain passing longitudinally through the element, and positively prevents the plates from moving endwise relatively to each other (or "creeping" upon each other) whereby the solder joint is relieved of all strain, while when the solder joint fuses this same part, B, rocks about its knife-edge surfaces of contact with the shoulders, C, C' and forces the plates apart—directly away from each other. The rocking strut has line or knife-edge-like bearing surfaces, B', B'', which 100 bear against the shoulders, C, C', and these bearing surfaces lie in the plane of its major axis, which is approximately parallel with the adjacent faces of the plates and with the line of strain passing through the 105 element when intact. This may be accomplished by making the part, B, of elliptical

cross section as shown in Fig. 1 or by forming it with knife edge bearing surfaces as shown in Fig. 3.

Assuming the parts to be in normal positions and condition, as shown in Fig. 1, the line of strain, so long as the solder joint holds, is through the major axis of the rocking strut and at right angles to the shoulders, C, C', as indicated by the line *a*. But as soon as the solder joint fuses and permits of the separation of the parts, several lines of strain develop. One will be upon the line, *b*, which extends from the line of contact between the bearing surface, B', with the shoulder, C, to the line or point of contact between the plate, A, and the lever-arm F, and the other will be upon the line, *c*, which extends from the line of contact between the bearing surface, B'', with the shoulder, C', to the line or point of contact between the plate, A', and the lever-arm, F'. These two lines, *b* and *c*, are parallel, but upon opposite sides of the major axis of the rocking strut, so that the tendency will be to rock the latter about its bearing surfaces in the directions indicated by the arrows in Fig. 1. This effectually moves the plates away from each other and permits them to fall apart, thus entirely releasing the part or parts which the element normally holds in normal position.

What I claim as new is:—

1. An element for automatic fire extinguishers having in combination two identical plates arranged face to face, and having shoulders disposed at right angles to the plane of the adjacent surfaces of said plates and at equal distances from their mid-length, thereby forming a recess, a rocking strut occupying said recess and having line-bearing-surfaces contacting with said shoulders respectively, said plates having bearing surfaces adapted to contact with the parts to be held in normal positions, said bearing surfaces being located upon opposite sides of a plane passing through the lines of contact between the rocking strut and the shoulders.

2. An element for automatic fire extin-

guishers having, in combination, two identical plates arranged face to face and offset at right angles on opposite sides of their mid-length, thereby providing oppositely presented shoulders disposed at right angles to the plane of the meeting surfaces of the plates and forming between said plates a recess or pocket, a rocking strut occupying said recess or pocket said strut being of elliptical cross section in a plane which is perpendicular to said shoulders and also to the meeting surfaces of the plates whereby said strut has line-bearing-surfaces contacting with the shoulders, respectively, in a plane parallel with the plates, said plates having also bearing surfaces adapted to contact with the parts to be held, the bearing surfaces last aforesaid being located in proximity to a plane passing through the points of contact between the rocking strut and the shoulders on the plates.

3. An element for automatic fire apparatus having, in combination, two identical overlapping plates, offset at right angles on opposite sides of their mid-length, thereby providing at opposite ends of the element, end portions having surfaces which contact with each other in parallel planes and providing also oppositely presented shoulders having bearing surfaces lying in parallel planes at right angles to the planes first aforesaid and leaving between said shoulders and overlapping portions of the plates, a recess or pocket, a rocking strut occupying said recess or pocket and having line-bearing-surfaces contacting with said shoulders in a common plane between and parallel with the planes of contact of the aforesaid contacting end portions of the plates, said contacting end portions being soldered together whereby when the parts are assembled and the solder joint remains intact, the line of strain will be approximately in the common plane of the lines of contact between the rocking strut and the shoulders.

EMANUEL M. COOK.
